ANTIVIRAL COMPOSITIONS AND METHOD OF ADMINISTRATION

Andrew Stephen Tomcufcik, Tappan, Robert Bruce Angier, Pearl River, Martin Forbes, New City, and Howard Frederick Lindh, Monsey, N.Y., assignors to American Cyanamid Company, Stamford, Conn., a corporation of Maine

No Drawing. Filed June 28, 1963, Ser. No. 291,282
11 Claims. (Cl. 167—65)

This invention relates to methods of and new compositions for treating viral infections in warm blooded animals.

Heretofore no chemotherapeutic agents have been found which have proved effective in treating systemic virus infections. We have now found that compositions containing as an active ingredient a compound of the following formula are useful in treating viral infections in warm blooded animals:

R is hydrogen or lower alkyl, R₁ and R₂ are hydrogen or lower alkyl, R₃ and R₄ are lower alkyl, X is lower alkylene, Z is oxygen or sulfur and acid addition and quaternary salts thereof.

The free bases of the compounds of this invention are, in general, oily liquids or low melting solids. They are, in general, soluble in water and in the usual organic solvents, such as lower alkanols, acetone, lower alkyl esters of lower alkanols, benzene, toluene, ethers and the like.

The free bases of the compounds of this invention form acid addition salts with acids such as hydrochloric, hydrobromic, sulfuric, acetic, citric, tartaric, lactic, succinic, maleic, phosphoric, malic, gluconic, ascorbic, 1,1'-methylene-bis-(2-naphthol-3-carboxylic acid), butane-1,2,3,4-tetracarboxylic acid and the like. Such acid addition salts are in general soluble in water, but not soluble in non-polar organic solvents such as ethers and petroleum ethers; and they may be prepared, in general, by adding an anhydrous acid to an anhydrous solution of the basic compound in ether or alcohol and thereafter isolating the precipitated salt by filtration.

The compounds of the present invention can be prepared by methods described hereinafter in the examples and in the prior art. The most general method for preparing the present compounds is the reaction of 1-carbethoxy-4-lower alkylpiperazine with a di-loweralkylamino lower fatty acid alcohol. Other methods are shown hereinafter in the examples.

One of the compounds of the present invention, diethylaminoethyl 4-methyl-1-piperazinecarboxylate, has shown a reproducible protective effect in experimental influenza A virus infections in mice. The results of tests are summarized in the following Table I.

2

TABLE I.—EFFECT OF 2-DIETHYLAMINOETHYL 4-METHYLPIPERAZINE-1-CARBOXYLATE IN INFLUENZA INFECTION IN MICE

5		Single dose treatment	
		Survivors/Group on 14th day after Infection	
10	Single Dose, mg./kg.	Oral Treatment	Subcutaneous Treatment
	1,600	72/100	Toxic
	800	70/100	25/40
	400	37/100	21/40
	200	7/80	11/40
15	Controls (0.85% NaCl)	5/100	1/40

Animals: Taconic male white mice; 16-20 grams body weight.
Infection: Intranasal; 0.05 ml. of a $10^{-6.4}$ broth dilution of virus stock
No. 67.
Treatment: Single dose directly into nostril.

20 Treatment: Single dose directly after infection; oral doses by tubing of 1.0 ml. volume of aqueous solution; subcutaneous doses by injection of 0.5 ml. volume of aqueous solutions; all solutions adjusted to pH 7.0.

The above Table I summarizes the results with a single dose as treatment directly after infection. The following Table II summarizes results with three dose oral treatment.

TABLE II.—EFFECT OF 2-DIETHYLAMINOETHYL
4-METHYLPIPERAZINE-1-CARBOXYLATE IN
THE INFLUENZA INFECTION IN MICE

30		Three dose oral treatment	
		Each Dose, mg./kg.	Survivors/Group and Survival Time (Days) on 14th Day After Infection
35		1,600	5/20
		800	15/20
		400	10/20
		Controls (0.85% NaCl)	2/20

Animals: Taconic male white mice; 16-20 grams body weight.
Infection: Intranasal; 0.05 ml. of a $10^{-6.4}$ broth dilution of virus stock No. 67.
Treatment: Oral tubing of 1.0 ml. volume of aqueous solutions at 0, 24 and 48 hours after infection.

Other compounds of the present invention were injected subcutaneously and the results obtained are summarized in the following Table III.

TABLE III.—EFFECT OF OTHER COMPOUNDS ON SURVIVAL RATIO OF MICE INFECTED WITH INFLUENZA A (PR-8 VIRUS)

	Name	Dose, mg./kg.	Survival Ratio on 14th Day
55			
	Dimethylaminoethyl 4-methylpiperazine-1-carboxylate.	800.....	5/15
	3-Dimethylaminopropyl 4-methylpiperazine-1-carboxylate.	800.....	5/15
30	2-Dimethylaminoisopropyl 4-methylpiperazine-1-carboxylate.	800.....	5/15
	Controls.....	(0.85% NaCl).....	5/105

Animals: Taconic Farms male white mice; 19-25 grams body weight
Infection: Intranasal; 0.05 ml. of a $10^{-6.3}$ dilution in brain heart infusion
broth of stock PR-8 virus.

5 Treatment: Compounds dissolved in water, pH adjusted to 7.0. Indicated dose injected subcutaneously immediately after infection. Controls received 0.85% NaCl solution.

The compounds of the present invention described above will be dispensed in compositions comprising the active ingredient and excipients including a carrier. While the amount of active ingredient to be given daily will depend on many factors such as the size, weight, age, kind, and severity of infection, etc. of the warm blooded animal, a daily intake ranging from 5 to 500 milligrams per kilogram of body weight will produce good results. The dosage unit may vary from 0.05 to 2 g. and may be in a form to be administered one or more times per day, or in smaller forms for multiple daily, or other more frequent administration. Any of the usual dosage unit forms of pharmaceutical compositions can be useful, for example, tablets, Oblets, hard or soft shell capsules, parenteral solutions or suspensions, oral solutions or syrups, etc.

Tablets or Oblets may include, in addition to active ingredient, any of the following excipients. A binder such as acacia, corn starch, gelatin, or the like. A disintegrating agent such as corn starch, potato starch, alginic acid, or the like. A lubricant such as stearic acid, magnesium stearate, talc or the like. Also a sweetening agent such as saccharin or sucaryl, and/or a flavoring such as peppermint oil, oil of wintergreen, or orange or cherry flavoring can be used.

Capsules may include, in addition to active ingredient, a lubricant and also an inert filler such as lactose, sucrose, corn starch or the like.

Solutions, usually include an acid such as hydrochloric, citric, tartaric, succinic, maleic, ascorbic, phosphoric or the like, or a suitable buffer thereof. Suspensions include a surfactant such as polyoxyethylene sorbitan monooleate (a complex mixture of polyoxyethylene ethers of mixed partial oleic esters of sorbitol anhydrides); oxyethylated tertiary octylphenol formaldehyde polymer; p-isoctyl-polyoxyethylenephenol polymers or the like; a suspending agent such as polyethylene glycol 4000 USP (a condensation polymer of ethylene oxide and water, represented by the formula: $\text{HOCH}_2(\text{CH}_2\text{OCH}_2)_n\text{CH}_2\text{OH}$, wherein n varies from about 70 to 85, the molecular weight being about 4000), carboxy methylcellulose (sodium carboxymethylcellulose USP, the sodium salt of carboxymethyl ether of cellulose having a closely controlled number of sodium carboxymethyl ($-\text{CH}_2\text{COONa}$) groups introduced into the cellulose molecule to bring about solubility in water); methylcellulose (cellulose methyl ether prepared from wood pulp or chemical cotton by treatment with alkali and methylation of the alkali cellulose with methyl chloride), and the like; and a buffer such as a phosphate, citrate, or tartrate buffer. Both solutions and suspensions may include a stabilizer such as disodium salt of ethylenediaminetetraacetic acid, sodium sulfite, monothioglycerol, or the like; and a preservative such as benzyl alcohol, parabens (methyl and propyl esters of p-hydroxybenzoic acid), or the like.

Oral solutions may include a suspending agent or viscosity control such as magnesium aluminum silicate, carboxymethylcellulose or the like as well as a buffer, preservative, etc. Solutions and suspensions may be of the aqueous sugar or sorbitol type. It is also known in pharmaceutical practice to employ a propyleneglycol type solvent for use with drugs.

The invention is further illustrated by means of the following examples.

Example I.—Preparation of 2-dimethylaminoethyl-piperazine-1-carboxylate

In a flask connected to a condenser and receiver is placed 817 g. of 2-dimethylaminoethanol, which contains 8 g. of dissolved sodium, and 474 g. of 1-carbethoxypiperazine. The mixture is heated first between 60°–70° C. for 7 hours at 32–38 mm. pressure and then at 140° C. for 7 hours at atmospheric pressure. The resultant solution is carefully fractionated at reduced pressure to remove excess 2-dimethylaminoethanol and unreacted 1-carbeth-

oxypiperazine. A crude fraction, boiling point 140°–160° C. at 15–25 mm. is collected and redistilled to yield 2-dimethylaminoethyl piperazine-1-carboxylate, a colorless oil, boiling point 114°–117° C./0.5–1 mm., n_{D}^{25} 1.4823.

Example II.—Preparation of 2-diethylaminoethyl-piperazine-1-carboxylate

Four g. of sodium are dissolved in 928 g. of 2-diethylaminoethanol and 474 g. of 1-carbethoxypiperazine are added to the solution. The mixture is then heated in a manner similar to that described in Example I, first at reduced pressure, in this case at 40 mm. for 7 hours at 88° C., and then at the boiling point of 2-diethylaminoethanol for 7 hours at atmospheric pressure. The 2-diethylaminoethyl piperazine-1-carboxylate is a colorless oil, boiling point 144.5°–147° C./4 mm., n_{D}^{25} 1.4803.

Example III.—Preparation of 2-diethylaminoethyl 4-methylpiperazine-1-carboxylate

A mixture of 468 g. of 2-diethylaminoethanol containing 4 g. of dissolved sodium and 172 g. of 1-carbethoxy-4-methylpiperazine is heated under reduced pressure and at atmospheric pressure in a manner similar to that described in Example II. Purified material consists of 2-diethylaminoethyl 4-methylpiperazine-1-carboxylate, a colorless oil, boiling point 127°–128° C./1 mm., n_{D}^{25} 1.4700.

Example IV.—Preparation of 2-diethylaminoethyl 4-methylpiperazine-1-carboxylate dihydrochloride

A salt is prepared by passing hydrogen chloride gas into an ethereal solution of 2-diethylaminoethyl 4-methylpiperazine-1-carboxylate of Example III. The product, 2-diethylaminoethyl 4-methylpiperazine-1-carboxylate dihydrochloride, is obtained as a white solid which melts after recrystallization from alcohol-ether at 196.3°–198.3° C. with effervescence.

Example V.—Preparation of 3-diethylaminopropyl 4-methylpiperazine-1-carboxylate

Metallic sodium (0.4 g.) is dissolved in 51.5 g. (0.39 mole) of 3-diethylamino-1-propanol followed by the addition of 17.2 g. (0.1 mole) of 1-carbethoxy-4-methylpiperazine. The solution is heated in an oil bath at 80°–90° C. for seven hours under reduced pressure (25–50 mm. of Hg) and then refluxed for ten hours at atmospheric pressure. The excess aminoalcohol is removed on a steam bath at 20 mm. of mercury and the residue is distilled through a small Vigreux column. The fraction boiling at 114–123° C. (0.6 mm. of Hg) is collected; yield 11.2 g., n_{D}^{25} = 1.4702. This product is redistilled through a Nester-Faust spinning band column, yield 7.5 g., boiling point 126–128° C. (0.9 mm. of Hg), n_{D}^{25} = 1.4712.

Example VI.—Preparation of 2-dimethylaminoisopropyl 4-methylpiperazine-1-carboxylate

Metallic sodium (0.4 g.) is dissolved in 41.3 g. (0.4 mole) of 1-dimethylamino-2-propanol. To this solution is added 17.2 g. (0.1 mole) of 1-carbethoxy-4-methylpiperazine and then heated for six hours at 80–90° C. A stream of dry air is passed through the reaction mixture at the beginning of the heating period. This causes 15 ml. of the aminoalcohol to distill over which is added back to the reaction. At the end of the six hours several ml. of distillate are collected before refluxing for an additional eight hours. The mixture is filtered and the filtrate is distilled through a Nester-Faust spinning band column, yield 2.4 g., boiling point 84–88° C. (10.4 mm. of Hg), n_{D}^{25} = 1.4662.

Example VII.—Preparation of 2-dimethylaminoethyl 4-methylpiperazine-1-carboxylate

To 36 g. (0.4 mole) of 2-dimethylaminoethanol is added 4.6 g. (0.2 mole) of sodium followed by brief refluxing to complete solution. The solution is then cooled to room temperature, diluted with 50 ml. of diglyme and 22.5 g. (0.11 mole) of 4-methylpiperazine-1-carbonyl chloride

5

is added. This is stirred at room temperature for a half hour then refluxed for two hours. After having been cooled to room temperature the reaction mixture is filtered and the filtrate heated on a steam bath at 20 mm. of Hg to remove the diglyme and excess 2-dimethylaminoethanol. The residue is distilled through a Nester-Faust spinning band column to give 9.6 g. of product, boiling point 83-85° C. (0.08 mm. of Hg), $n_{D}^{20} = 1.4714$.

Example VIII.—Preparation of 2-diethylaminoethyl 4-methylpiperazine-1-carbothiolate dihydrochloride

2-diethylaminoethanethiol hydrochloride (32.8 g., 0.193 mole) is dissolved in 25 ml. of water and covered with 100 ml. of ether. Approximately 50–60 g. of anhydrous potassium carbonate is added followed by vigorous shaking. The ether layer is decanted and the remaining slurry is shaken with three additional 100 ml. portions of ether. The combined ether extracts are dried over magnesium sulfate, then evaporated to dryness to yield 23.8 g. (0.164 mole) of the free base. This material is dissolved in 70 ml. of diglyme, 3.8 g. (0.164 mole) of sodium is added and warmed on a steam bath to effect solution. The solution is cooled to room temperature, 16.3 g. (0.082 mole) of 4-methylpiperazine-1-carbonyl chloride is added, and the reaction mixture is stirred at room temperature for one-half hour, then refluxed for two hours. The insoluble portion is filtered off and washed with 100 ml. of diglyme. The filtrate and washings are combined and the diglyme is removed on a steam bath at 20 mm. of Hg. The residue is again filtered from some solid material and the filtrate is distilled through a Nester-Faust spinning band colum. The fraction boiling at 120–122° (0.075–0.10 mm. of Hg) is collected; yield 12.4 g. of 2-diethylaminoethyl 4-methylpiperazine-1-carbothiolate, $n_{D}^{26} = 1.5110$.

The above product is dissolved in 50 ml. of anhydrous ether and treated with 300 ml. of anhydrous ether which has previously been saturated with anhydrous hydrogen chloride in an ice-bath. The resulting gum which separates is triturated to a solid, filtered and recrystallized from ethanol-ether; yield 12.7 g., melting point 229°-234° C. dec.

Example IX.—Preparation of 2-diethylaminoethyl 2,4,5-trimethylpiperazine-1-carboxylate

Metallic sodium (0.4 g.) is dissolved in 46.8 g. of 2-diethylaminoethanol followed by the addition of 20.0 g. of 1-carbethoxy-2,4,5-trimethylpiperazine. This is treated in a manner similar to Example V. The product obtained is 2-diethylaminoethyl-2,4,5-trimethylpiperazine-1-carboxylate.

Example X

Parenteral solutions of the compounds of the present invention can be used as a method of administration. An illustrative formulation is the following.

	Percent w/v.
Diethylaminoethyl 4-methyl-1-piperazinecarboxylate	25-100
Hydrochloric acid as needed to obtain pH, q.s.	
to pH 4.5-5.5.	
Sequestrene, disodium	0.05
Benzyl alcohol reagent	0.9-1.5
Pyrogen-free distilled water to make 100.00 ml.	

The pH of the above solution is about 4.5-5.5. The 65 solution may be dispensed in a single ampule for multiple dosage or in 20 ampules for single dosage.

In place of hydrochloric acid other acids can be used such as citric, succinic, lactic, maleic, tartaric, gluconic, ascorbic, phosphoric, 1,1'-methylene-bis-(2-naphthol-3-carboxylic acid) and the like. Preservatives other than benzyl alcohol can be used, such as for example, chlorobutanol, parabens, etc. Other stabilizers than sequestrene disodium can be used such as, for example, sodium bisulfite, monothioglycerol and the like.

6

Example XI

The compounds of this invention may be administered in oral syrup preparations such as the following.

		Percent w./v.
5	Diethylaminoethyl 4-methyl-1-piperazinecarboxylate	25-100
	Sodium phosphate monobasic, sodium phosphate dibasic, q.s. to pH 4.5-5.5.	
10	Methylparabens	0.08
	Propylparabens	0.02
	Sucrose	10-40
	Red Dye FDC #2	0.005
	Cherry flavor	0.05
15	Distilled water q.s. ad. 100 ml.	

The above syrup has a pH of about 4.5-5.5.

The above syrup has a pH of about 4.5-5.5.

Other ingredients may replace those indicated above for example a suspending agent such as bentonite magma, tragacanth, carboxymethylcellulose, methylcellulose, car-
20 bopol 934 (carboxy vinyl polymer of high molecular weight), etc. can be used. The phosphates used above as buffers can be replaced with citrates or tartrates. As preservatives, the parabens can be replaced with alkali metal benzoates, sorbic acid or the like. The sugar and
25 sorbitol could be replaced in whole or in part with corn syrup, glycerol, other sugars, etc. And alternate dyes and flavors could replace those indicated above.

Example XII

30 The compounds of this invention may be dispensed in hard or soft shell capsules. A useful formulation for preparing such capsules is as follows.

35 Diethylaminoethyl 4-methyl-1-
piperazinocarboxylate ----- 25.0
Magnesium stearate ----- 0.1250
Mix thoroughly and dispense in 50 capsules

Example XIII

The compounds of this invention may be dispensed as pharmaceutical tablets or Oblets. A useful formulation for preparing tablets or Oblets is as follows:

	Per tablet, g.
45 Diethylaminoethyl 4-methyl- 1-piperazinecarboxylate	50.0
Corn starch	2.0
Methylcellulose (viscosity 400 cps.)	0.50
Magnesium stearate, 1%	0.525

50 Mix thoroughly and dispense as 100 tablets

The above tablets each containing 0.5 g. of active ingredient may be considered to provide an entire single daily dose. Such a tablet might be scored so as to provide fractional daily doses. Alternatively, tablets containing smaller amounts of active ingredient might be prepared for fractional daily or smaller doses.

We claim:

1. A method of treating virus infections in warm blooded animals which comprises administering to said animals an antiviral composition comprising an edible carrier and from 5 to about 500 mg. per kg. based on body weight of said animal, of a substituted piperazine of the formula:

70 wherein R is selected from the group consisting of hydrogen and lower alkyl, R_1 and R_2 are selected from the group consisting of hydrogen and lower alkyl, R_3 and R_4 are lower alkyl, X is lower alkylene, Z is selected from the group consisting of oxygen and sulfur and acid 75 addition and quaternary salts thereof.

2. The method of claim 1 in which the substituted piperazine is 2-diethylaminoethyl-4-methylpiperazine-1-carboxylate.

3. The method of claim 1 in which the substituted piperazine is 3-diethylaminopropyl-4-methylpiperazine-1-carboxylate.

4. A method of claim 1 in which the substituted piperazine is 2-dimethylaminoisopropyl 4-methylpiperazine-1-carboxylate.

5. The method of claim 1 in which the substituted piperazine is 2-dimethylaminoethyl 4-methylpiperazine-1-carboxylate.

6. The method of claim 1 in which the substituted piperazine is 2-diethylaminoethyl piperazine-1-carboxylate.

7. A composition of matter having antiviral activity, in dosage unit form, comprising a pharmaceutical carrier and from about 0.05 to 2 g. of a substituted piperazine of the formula:

20

wherein R is selected from the group consisting of hydrogen and lower alkyl, R₁ and R₂ are selected from the group consisting of hydrogen and lower alkyl, R₃ and R₄ are lower alkyl, X is lower alkylene, Z is selected from the group consisting of oxygen and sulfur and acid addition and quaternary salts thereof.

8. A composition of matter in accordance with claim 7 characterized in that the substituted piperazine is 2-diethylaminoethyl 4-methylpiperazine-1-carboxylate.

9. A composition of matter in accordance with claim 7 characterized in that the substituted piperazine is 3-diethylaminopropyl 4-methylpiperazine-1-carboxylate.

10. A composition of matter in accordance with claim 7 characterized in that the substituted piperazine is 2-dimethylaminoisopropyl 4-methylpiperazine-1-carboxylate.

11. A composition of matter in accordance with claim 7 characterized in that the substituted piperazine is 2-dimethylaminoethyl 4-methylpiperazine-1-carboxylate.
